W. H. GOLDING

WRENCH

Filed Feb. 28, 1924

Fig. 1.

William H. Golding,

DeWitt R. S. A.

inventor.

Attorney

UNITED STATES PATENT OFFICE.

WILLIAM H. GOLDRING, OF MERRICK, NEW YORK.

WRENCH.

Application filed February 28, 1924. Serial No. 695,770.

To all whom it may concern.

Be it known that I, WILLIAM H. GOLDRING, a citizen of the United States, residing at Merrick, County of Nassau, State of New York, have invented certain new and useful Improvements in Wrenches, of which the following is a specification.

This invention relates to wrenches, having for an object to provide means of an improved nature for permitting adjustment of the sliding jaw relative to the fixed jaw and maintaining the same firmly in adjusted positions.

A further object of the invention is to provide a wrench of that character wherein a sliding jaw is employed movable toward and away from the fixed jaw, and wherein means are provided for simultaneously locking the jaw against movement away from the fixed head and at the same time forcing the movable jaw into clamping engagement with the object to be gripped.

Still further and particular objects are to provide a wrench of the type and for the purposes stated which is of extremely simple construction, which is composed of but few simple and inexpensive parts all capable of being easily and quickly assembled, which has its parts so constructed and arranged as to minimize the opportunity for wear, breakage and derangement, which is positive and quick in action, which is capable of being marketed at low cost, and which will prove highly effective in use.

With these and other objects in view, the invention consists of the features of construction, combination and arrangement of parts, hereinafter fully described and claimed, reference being had to the accompanying drawing, in which:

Figure 1 is a side elevation of a wrench constructed in accordance with the invention and showing the parts in the position they will assume when the movable jaw is in locked or fixed position;

Fig. 2 is a similar view, parts broken away, and illustrating the parts as they will appear when the sliding jaw is free for movement; and

Fig. 3 is a transverse sectional view taken substantially upon line 3—3 of Fig. 1.

Referring now more particularly to the drawing, 4 indicates the shank of a familiar type of wrench with which the present invention is associated, and this shank is pro-

vided at one end with the fixed or immovable head 5 and terminates at its opposite end in a hand grip portion 6. This shank is straight throughout its length, and is of substantially rectangular shape in cross-section, being channeled longitudinally as at 7 upon its opposing faces to provide a keyway or guide groove for the inwardly projecting members or keys 8 of the sliding head or jaw 9. The head or jaw 9 encloses the shank 4 so as to be slidable thereon toward or away from the fixed head 5 and is limited in its outward sliding movement by means of a pin 10 passed through the shank at a proper point. This head may be a screw member or it may be a pin of any other type tightly fitted in the shank.

The forward face of the sliding jaw 9 is cut away so as to provide a recess 11 communicating with the forward edge or face 75 of the shank 4, and in this recess is arranged a gripping member indicated at 12. This member is preferably of slightly less length than the length of the recess 11, and is provided at its base with a flat face 13 to rest 80 upon the corresponding face of the jaw 9 at the lower end of recess 11. The member 12 has its lateral edges inclined inwardly slightly toward its outer end, and these inclined faces are provided with teeth 14. 85 The outer extremity of the grip member is rounded in a substantially cam shape as at 15, for a purpose to be hereafter stated. The adjacent forward face of the shank 4 is provided with a series of teeth indicated 90 at 16, to be gripped and interlocked with the teeth 14 of the gripping member 12.

The gripping member 12 is provided inwardly from its ends with a transverse opening to receive a pin 17; the latter being held 95 between arms 18 at the outer end of an operating handle or lever 19. The arms 18 straddle the slidable jaw 9, and washers 20 may be interposed between the inner faces of these arms and the next adjacent faces 100 of the gripping member 12, as illustrated particularly in Fig. 3.

The lever 19 at substantially the juncture of the arms 18 with the body portion thereof, is provided with a tooth, projection or 105 detent indicated at 21, and which is adapted to engage with teeth 22 upon the rear face of the shank 4.

The lever 19 is shaped so as to be conveniently gripped by the hand of the oper- 110

ator of the wrench, and is normally held in outward position by a spring 23 secured at one end to the lever and resting at its opposite end against the hand grip portion 5 of the shank.

The lever has its detent 21 and gripping member or head 12 so associated thereon that normally, that is, when the lever is extended by means of the spring 23, the gripping member 12 will be moved out of engagement with the teeth 16 on the forward face of the shank 4, while the detent 21 is out of engagement with the teeth 22 on the rear face thereof. At this time, the detent 15 21 will be engaged with the rear portion of the sliding jaw member 9 and seated within a suitable recess, opening or bevel portion 24 formed in the said rear portion of the sliding jaw. With the parts thus normally 20 positioned, it is evident that free sliding movement of jaw 9 is permitted without interference in any way with the teeth 16-22 of the shank. It is when the parts are so 25 positioned that adjustments of the jaw 9 are made, and when the proper adjustment has been determined, the operator moves the lever 19 inwardly toward the hand grip 6. This action causes the detent 21 to move out of its position upon the rear face of jaw 30 9 and into engagement with the next adjacent tooth 22, upon which the detent fulcrums. Further movement of lever 19 then causes the head member 12 to move inwardly toward the forward face of shank 4, and, 35 due to the particular inclination of the adjacent face of the gripping member, the lowermost tooth or teeth thereof will first engage with the adjacent shank teeth. This operates to maintain the shank against any 40 outward sliding movement, and further depression of the lever 19 eventually causes all of the teeth 14 of the gripping member to engage with the next adjacent teeth of the shank and at the same time the outer 45 rounded or cam end of the gripping member moves into engagement with the next adjacent surface of the recess 11 of the jaw. This engagement of the gripping member with the jaw causes the latter to exert a 50 slight pressure inwardly upon the article being gripped, whereupon a tight and firm connection between the wrench and the gripping member is assured, and danger of slippage of the tool upon the work is thus 55 avoided. The degree of this additional gripping action of head 9 may be governed accurately by causing the detent 21 to engage within a proper or desired tooth 22 upon the rear edge of shank 4. For instance, it is apparent that with the detent 60 21 engaged in the space between the teeth next adjacent thereto (Fig. 2) inward pressure upon lever 19 will cause the jaw 9 to receive a relatively greater degree of outward or gripping movement than would be 65

experienced were the detent 21 to be engaged in the next adjacent tooth to the one above specified.

By providing both the opposing inclined faces of the gripper member 12 with teeth, 70 in the event that the teeth of one side become worn it is but necessary to remove the head and invert it, so that the teeth formerly upon the outer surface are positioned so as to cooperate with the teeth of the wrench 75 shank.

It is apparent from the foregoing that I have provided a wrench capable of carrying forth the several objects in a most expeditious way, and the operation and adjustment of which is at once apparent to all. The simplicity of the construction of the wrench is such that while a great degree of gripping pressure is obtained, danger of wear, breakage or derangement of any of 85 the movable parts of the wrench is minimized.

While the above is a disclosure of the invention in its preferred form, it is apparent that the same may be susceptible to 90 changes or variations in the minor details of construction, arrangement and assemblage of parts, and it is to be understood that I reserve to myself the right to make such alterations as may be deemed necessary or practicable without departing from the spirit of the invention as defined by the 95 claims.

Having thus fully described my invention, I claim:

1. In a wrench, a shank, a jaw member 100 slideable upon said shank, a lever associated with said jaw member, gripper members wholly detached from said jaw arranged in spaced relation upon said lever and adapted 105 when the lever is moved in one direction to engage simultaneously with opposing faces of said shank, and one of said members being movable laterally and independently 110 of said jaw member.

2. In a wrench, a shank, teeth upon opposing faces of said shank, a jaw member 115 slideable upon said shank, a gripper member associated with said jaw and movable laterally of the same, a lever connected at one end to said gripper member, and a detent on said lever removed from said gripper member and adapted to be moved into or out of contact with the teeth of said shank.

3. In a wrench, a shank, teeth upon the 120 opposing faces of said shank, a jaw member slideable upon said shank and having a recess in its forward face communicating with the teeth of the corresponding portion of said shank, a gripper member arranged 125 in said recess, teeth on said member to engage with the teeth of said shank, a lever, arms at one end of said lever straddling said jaw and pivoted to said gripper member, and a detent on said lever removed 130

from said gripper member and adapted to engage with the next adjacent teeth of said shank.

4. In a wrench, a shank, teeth upon the forward and rear edges of said shank, a jaw slideable upon said shank and having a recess in the forward face thereof exposing the teeth of the corresponding edge of the shank, a gripper member having teeth thereon arranged in said recess, a lever, arms at one end of said lever straddling said shank and said jaw and pivot-

ally connected with said gripper member, the said arms approaching said gripper member from the rear edge of said shank, 15 a detent on said lever adapted to engage the teeth upon the rear face of said shank, and a spring normally holding said lever with the detent and gripper member disengaged from said teeth. 20

In testimony whereof I affix my signature.

WILLIAM H. GOLDING.
